UNITED STATES PATENT OFFICE

CLAUDE A. BULKELEY, OF KENMORE, NEW YORK, ASSIGNOR TO NIAGARA BLOWER COMPANY, OF BUFFALO, NEW YORK, A CORPORATION OF NEW YORK

CLIP

Application filed December 16, 1930. Serial No. 502,821.

My present invention relates to a clip of a form and construction particularly suited for use in the stretching of hides and like articles. The clip, in its general plan of construction and operation, is similar to the clip disclosed in my copending application Serial No. 473,147, filed August 5, 1930, and, like the clip shown therein, is designed to be used in supporting a hide upon a perforated sheet metal face plate of a stretching frame. When used in this connection a plurality of clips grip the edges of the hide and are maintained in stretching relation by engagement of appropriate means on the several clips in the perforations of the face plate of the stretching frame.

The clip which forms my present invention, like that of my copending application, has a finger piece or handle by means of which it may be pulled to draw the hide taut, and a spring connection between its hide-gripping and frame-engaging parts which serves to prevent tearing of the hide at its places of connection with the clips, either from the use of excessive force in drawing the hide taut or from shrinkage of the hide in drying.

My invention relates generally to a clip comprising a part adapted to be engaged with a stretching frame, a part having gripping jaws thereon, and spring tension means between the parts and tending to draw them together. More particularly, my present invention resides in a construction of clip embodying improvements in several features, including the frame-engaging means, the gripping means, the bearing support for the movable gripping jaw, the form and arrangement of the tensioning spring, and the means for attaching the spring to the parts of the clip.

The principal objects of my invention are to provide a clip which not only can be quickly and easily manipulated with one hand in placing it in position and removing it from a hide-stretching frame, and which reliably grips the hide and holds it in stretched condition on the frame, without danger of tearing or loosening, but which is also composed of a minimum number of parts so constructed,

arranged, and proportioned as to produce a comparatively short, more compact, and more convenient device, and one that may be more readily and more economically manufactured and in which the necessity of repairs or replacements under severe and long-continued use are reduced to a minimum.

In the accompanying drawings:

Figure 1 is a side elevational view of a clip or fastener embodying my present invention, showing the same holding a hide or the like upon a stretching frame.

Figure 2 is a top plan view of the clip removed from the frame.

Figure 3 is a longitudinal sectional view taken on line 3—3 of Fig. 2.

Figure 4 is an enlarged top plan view of part of the frame-engaging part of the clip detached from the other parts.

Figure 5 is an end elevational view, taken from the left-hand end of Fig. 2.

Figure 6 is an enlarged sectional view looking down on line 6—6 of Fig. 3.

Figure 7 is an enlarged vertical sectional view of the assembled device, looking in the direction of the arrows on line 7—7 of Fig. 3, and

Figure 8 is an enlarged sectional view on line 8—8 of Figure 3, looking in the direction of the arrows.

The clip which constitutes my present invention may be used with any suitable stretching frame of usual and well-known construction, but the frame which I prefer to use forms the subject-matter of my copending application Serial No. 473,146, filed August 5, 1930.

In general such a frame consists of a sheet metal face plate 5 reinforced at its edges by angle irons 6 riveted or otherwise secured to the plate. The face plate is perforated throughout substantially its entire extent, the holes 8 being comparatively small, so that when the hide 9 is gripped at its edges by clips of a construction similar to that to which my present invention pertains, each clip can be caught in one of the holes 8 to fix it on the face plate, and, in conjunction with the other clips, to hold the hide 9 taut.

Generally speaking, the clip or fastener em-

bodying my present improvements comprises a gripping part 10 provided with means for gripping the hide, a frame-engaging part 11 slidable with respect to the gripping part, 5 and a spring tension device interposed between the relatively slidable parts and tending to draw them together.

The frame-engaging part 11, preferably made of sheet metal, comprises a flat plate 16 portion 20 with spaced pairs of upstanding flanged lips 21 thereon, a handle 22 and a finger 24 for engaging the holes 8 in the face plate. In my present improved construction this finger is made rounded to insure its 15 proper engagement with the periphery of any of the holes 8 and to prevent the wear which would result from use of a finger with sharp edges.

The gripping part 10, also preferably 20 made of sheet metal, consists of a tongue 12 adapted to slide on plate 20 between lips 21 and beneath the flanges thereof, the tongue being formed with a reverse lip 13 adapted to function as the lower gripping jaw of the 25 device, upstanding wings 14 on opposite sides of the tongue indented, as at 15, to permit the insertion of the edge of the hide into the gripping jaws, and carrying a pivot 19 for the movable upper gripping jaw 16. 30 The pivoted jaw 16 is formed with a handle 18 and has its gripping portion turned inwardly in a reverse lip or cam 17 to cooperate with lower gripping jaw 13. By reason of this reverse arrangement, cam 17 is drawn 35 more tightly into engagement with the hide when tension is applied to it, so that the hide is effectively prevented from slipping out through the jaws. The jaw 16 is shown as knurled, but either or both of the gripping 40 jaws may be milled or roughened to increase the gripping action upon the hide.

In releasing the hide from the clip, the handle of the movable jaw is prevented from 45 excessive turning movement by coming into contact with stops 35 on wings 14.

The gripping part 10 is slidably connected to the frame-engaging part 11 by the engagement of tongue 12 between the flat plate portion 20 of part 11, and the oppositely disposed pairs of guiding and retaining flanged lips 21 formed thereon.

The spring tension means interposed between the parts 10 and 11 preferably comprises a helical tension spring 25, the opposite ends 30, 31 of which are bent directly across the helix to form points of attachment to the relatively slidable parts of the clip, which points are practically coincident with the respective ends of the helix. By 60 this arrangement a material reduction in the over-all length of the clip may be effected.

The spring is secured to part 11 by the engagement of its end 30 with a lip 27 struck from handle 22. The other end of the spring 65 is attached to part 10, the lower lip 13 there-

of being extended for this purpose to form a spring-attaching member, preferably in the shape of a hook 32 adapted to engage the bent end 31 of the spring. The lower lip 13 may also be provided with additional supporting or strengthening means, to prevent it from being forced down by the pressure exerted against it by cam 17. For this purpose lip 13 or its hook extension 32 may be formed with feet 33 bent downwardly against or in close proximity to the lower portion of part 10, preferably on each side of the central lip or hook extension. 70

The spring 25 is preferably so constructed and arranged that, when installed in a clip for stretching hides, it begins to open at about fifteen pounds, any greater force which may be applied to the device, either manually or by shrinkage of the hide, being expended in stretching the spring and not being exerted upon the edges of the hide. 75

The aims of lessening the difficulties and expense of manufacture and lengthening the life of the device, realized in my novel spring-attaching means and other improved features, are also followed in the construction of the pivotal mounting of the upper gripping jaw 16. The pin 19 extends through reversely disposed bearing straps 37, 38 struck up from the slotted movable jaw member and through suitable openings in the side wings 14, and is preferably headed at each end, a shoulder 36 maintaining the wings in properly spaced relation to prevent binding and undue wear of the bearing. 80

In operating the clip the operator lifts the handle 18, thereby moving the cam portion 17 of the upper jaw away from the fixed lower jaw 13 and permitting the edge of the hide to be inserted between the jaws. Depression of handle 18 moves the cam 17 downwardly and forwardly and grips the edge of the hide between the cam 17 and lower jaw 13, the gripping action being increased when tension is put upon the hide. Grasping the handle 22, the operator then moves each clip outwardly to draw the hide 9 taut upon the perforated plate 5, and catches the finger or hook 24 of each of the clips in the proper opening 8 in the face plate to hold the hide in its taut condition. 90

I claim:

1. A fastener for holding hides or the like in a stretched condition on a frame, comprising a part having a gripping jaw and a spring support integral therewith, a support for a movable jaw and a gripping jaw movably mounted thereon, a part slidable relative to said first-mentioned part and provided with a spring support and a hook adapted to be engaged with said frame, and a spring attached to said spring supports and tending to draw said parts together. 105

2. A fastener for holding hides or the like in a stretched condition on a frame, comprising 110

ing relatively slideable parts, one of said parts having a spring-attaching member and a frame-engaging member, and another of said parts having a fixed gripping jaw and a movable jaw cooperating therewith, said fixed jaw having a spring-attaching member integral therewith, and a spring engaging said spring-attaching members and tending to draw said relatively slideable parts together.

10 3. In a fastener for holding hides or the like in a stretched condition on a frame, a frame-engaging part comprising a plate having a frame-engaging finger on its under side and oppositely disposed guide lips upon its upper side and provided with a spring-attaching member, a hide-engaging part comprising a tongue slidably engaging said plate between said guide lips and having thereon a reversely formed lower jaw, and upstanding side wings, said lower jaw being extended inwardly to form a spring-attaching hook, a movable jaw pivoted between said wings and having a cam portion movable toward said lower jaw to grip the edge of the hide therebetween, and spring tension means connected to said spring-attaching member and said spring-attaching hook and tending to draw said frame-engaging part and said hide-engaging part together.

30 4. A fastener for holding hides or the like in a stretched condition on a frame, comprising a part having a gripping jaw and a spring-attaching extension integral therewith and provided with a support for a movable gripping jaw pivotally mounted thereon, a part slideable relative to said first-mentioned part and provided with a spring-attaching member and a frame-engaging finger, and a helical spring having its ends turned directly across its helix and respectively connected to said spring-attaching extension and said spring attaching member, and tending to draw said parts together.

45 5. In a fastener for holding hides or the like in a stretched condition on a frame, a frame-engaging part having a handle and a depending finger adapted to be engaged in said frame, a hide-engaging part slideable relative to said frame-engaging part and having a fixed lower jaw, upstanding wings and a sheet metal movable jaw, said movable jaw comprising a handle portion, a bearing portion and a reversely extending cam jaw portion, said bearing portion being positioned between said wings and being slitted and struck up to form reversely disposed curved bearing straps, and a headed and shouldered pivot pin extending through said straps, supported upon said wings, and holding said wings in properly spaced relation to permit pivotal movement of said movable jaw, and a coil spring connected at its respective ends to said frame-engaging part and said hide-engaging part.

60 6. In a fastener for holding hides or the

like in a stretched condition on a frame having a plurality of apertures therein, a sheet metal frame-engaging part comprising a plate provided with a handle and a spring-attaching hook and having a rounded finger on its under side adapted to be engaged in one of said apertures, and oppositely disposed flanged guide lips upon its upper side, a sheet metal hide-engaging part comprising a tongue slidably engaging said plate between said guide lips and having thereon a reversely formed lower jaw and upstanding side wings, said lower jaw being extended inwardly to form a spring-attaching hook, and formed with depending feet adapted to engage and brace against said tongue, a sheet metal movable jaw pivoted between said wings and comprising a handle portion, a bearing portion, and a reversely-extending cam jaw portion movable toward said lower jaw to grip the edge of a hide therebetween, said bearing portion being slitted and struck up to form reversely disposed curved bearing straps, and a pivot pin extending through said straps and supported on said wings, and a helical spring having its ends bent directly across its helix and respectively connected to said spring-attached hooks.

In testimony whereof I hereby affix my signature.
